UNITED STATES PATENT OFFICE.

CHARLES A. GAY, OF SEATTLE, WASHINGTON.

DESIGN FOR A BADGE.

SPECIFICATION forming part of Design No. 22,410, dated May 9, 1893.

Application filed February 20, 1893. Serial No. 465,198. Term of patent 3½ years.

To all whom it may concern:

Be it known that I, CHARLES A. GAY, a citizen of the United States, residing at Seattle, in the county of King and State of Washington, have invented and produced a new and original Design for a Badge; and I do hereby declare the following to be a full, clear, and exact description of the invention, such as will enable others skilled in the art to which it appertains to make and use the same.

The figure shows my design which consists of the following features: A rectangular panel B, surrounded by the figure of a mountain A. Below this and with their tops touching the bottom of the panel near each end are the representations of two fir trees C, having their

bases upon the ends of a scroll D. Within the space formed by the panel, scroll and two trees is a representation of the bust and head of George Washington, E. The panel B and scroll D are intended for the insertion of any suitable or desired words.

What I claim is—

The design for a badge substantially as herein shown and described.

In testimony whereof I affix my signature in presence of two witnesses.

CHARLES A. GAY.

Witnesses:

H. L. REYNOLDS,
J. B. MURPHY.
